(57) **CLAIM**

The ornamental design for a gun cleaning case, as shown and described.

DESCRIPTION

FIG. 1 is a perspective view of a gun cleaning case having a bottom member and a top member of the gun cleaning case in a closed position, showing my new design;

FIG. 2 is a front elevation view of the gun cleaning case of FIG. 1, with the side and rear elevation views being identical;

FIG. 3 is a bottom plan view of the gun cleaning case of FIG. 1;

FIG. 4 is a top plan view of the gun cleaning case of FIG. 1;

FIG. 5 is a perspective view of the gun cleaning case, shown in an alternate configuration with the bottom member in an open position;

FIG. 6 is a front elevation view of the gun cleaning case, shown in another alternate configuration with the bottom member in an open position, with the rear elevation view being identical;

FIG. 7 is a top plan view thereof;

FIG. 8 is a bottom plan view thereof;

FIG. 9 is a perspective view the gun cleaning case, shown in an alternate configuration having the top member shown in an open position;

FIG. 10 a front elevation view of the gun cleaning case, shown in another alternate configuration having the top member shown in an open position, with the rear elevation view being identical; and,

FIG. 11 is top plan view of the gun cleaning case of FIG. 9. The broken lines shown in FIGS. 8 and 11 depict portions of the gun cleaning case that form no part of the claimed design.

1 Claim, 7 Drawing Sheets
